ECCENTRIC PISTON PUMP OR
COMPRESSORJohn O. Heinze, Detroit, Mich., assignor to Heinze
Development Company, Detroit, Mich., a cor-
poration of Michigan

Application November 15, 1935, Serial No. 49,913

2 Claims. (Cl. 103—131)

This invention relates to a pump or compressor of the oscillatory eccentric piston type.

In engines, pumps or compressors employing an eccentric oscillating piston, difficulty has always been experienced in preventing the products of combustion, fluid, or compressed air from leaking by the dividing wall or abutment to which the oscillating piston is pivotally connected from the intake to the exhaust side.

10 The present invention relates to a construction wherein the baffle wall or abutment is so constructed as to obviate the possibility of leakage from the intake to the exhaust side of the piston and to accomplish this desired end it is found most desirable that the pivot member upon which the piston oscillates, be positioned within the cross sectional area of the piston and be firmly anchored in the walls of the cylinder. This also facilitates the accurate location of the pin relative to the axis of the shaft and permits of the use of a baffle wall of extended cross sectional area and provides a very rigid pivotal support for the piston, also permitting the employment of bearing members for the pivot pin, free to turn upon 20 this pin as the piston oscillates and also with the piston free to reciprocate relative to these bearing members which are positioned within a transverse slot or recess in the piston extending transversely thereof with the ends of these bearing members abutting the end walls of the cylinder.

Further the present arrangement permits the use of an abutment wall of extended thickness which may be formed at its inner end to closely engage the bearing members which may be curved 35 concentric with the axis of the pivot pin and thus insure against leakage past the abutment; and it is also an object to provide an arrangement wherein the abutment wall may be provided with a shoe to engage the curved surfaces of the bearing members to make a tight joint, and this construction further lends itself to providing adequate lubrication of the contact surfaces and also adequate means may be provided for taking up 40 wear caused by the sliding contact between bearing members and walls of the piston slot in relation to which these members move as the piston oscillates within the cylinder.

With the above and other ends in view the invention consists in the matters hereinafter set forth and more particularly pointed out in the appended claims, reference being had to the accompanying drawings, in which

Fig. 1 is a transverse vertical section substantially upon the line 1—1 of Fig. 3, of a construc-

tion illustrative of an embodiment of the invention;

Fig. 2 is a sectional detail substantially upon the line 2—2 of Fig. 1;

Fig. 3 is a vertical section substantially upon the line 3—3 of Fig. 1, and

Fig. 4 is a cross sectional detail substantially upon the line 4—4 of Fig. 1.

As shown in the drawings, the pump or compressor comprises two cylinders placed side by side, each cylinder comprising an outer peripheral hollow ring 1 and hollow disk-like heads or ends 2 and a common intermediate head 3, the peripheral ring-shaped walls of the two cylinders being firmly secured between the heads 2 and in abutting relation to the intermediate head 3, by means of a plurality of transverse bolts 4 passing through the heads and peripheral ring walls to draw all into firm abutting relation.

The outer peripheral rings 1 are each formed hollow to provide a water circulating space between the outer wall of the ring and the inner wall 5 which forms the wall of each cylinder 6. Each of the ring members 1 is formed with a connecting rib or web 7 intermediate its ends, the space at each side of this rib forming a water space for the purpose of cooling the cylinder and these spaces are in communication through openings 8 in the web at each side of a thickened portion of the web which forms a stud 9 at opposite sides of the casing or cylinder structure and which studs are bored longitudinally to provide passages 10 which open into the cylinders 6, the outer ends of these passages being closed normally, by screw plugs 11 which may be removed for the purpose of allowing any accumulation of fluid within the cylinders to be drawn off. The circular disk-like piston 12 within each cylinder is also formed hollow with a hollow hub portion 13 adapted to receive a ring sleeve 14 between which and the exterior surface of an eccentric 15, roller bearings 16 are interposed. The eccentric 15 for each piston is secured to a shaft 17 in any suitable manner as by a key 18 and these eccentrics are positioned on the shaft with the eccentric for one piston having its large side extending in one direction from the shaft and the eccentric for the other piston extending in a diametrically opposite direction.

Connecting the hub wall 13 of each piston with the peripheral wall thereof, are parallel walls 19 and 20 which are spaced apart to form a slot 21 of extended width therebetween, this slot opening through the ends of each piston and

extending inwardly to adjacent the hub 13 thereof.

A tubular pivot pin 22 extends longitudinally of the slots 21 and wholly within said slots and 5 through the heads 2 and 3, this tubular pivot member being rigidly secured in place by nuts 23 on its outer ends engaging the outer sides of the heads 2.

Mounted upon the tubular pivot member 22 10 within the slot 21 of each piston, is a bearing block 24 made in halves to embrace the pivot pin and to engage the surface of the wall 19 and also the surface of a shim member 25 interposed between the other surface of the block and the other wall 20, 15 said shim being normally forced toward the block by means of coiled springs 26 to make and maintain a tight joint between the surfaces of the block and the surfaces of the wall 19 and shim 25, the expansive force of the springs 26 tending to rotate 20 the piston to bring the wall 19 into engagement with one side of the bearing block and exerting force against the opposite side of the block. The ends of these half bearings abut the end walls or 25 heads 2 and 3 of the cylinders and the outer ends 25 of the halves of the bearing block are formed concentric with the axis of the pivot pin 22 to closely fit at all times the inner end of an abutment member 27 having an outwardly extending rib or shank portion 27a to engage within a slot in the wall or 30 ring member 1 of the cylinder and is formed with shoulders to engage and closely fit against the inner curved surface of the cylinder wall, the inner end of this abutment wall 27 being formed concave to closely fit against the convex outer 35 ends or side of the two half bearings. This abutment 27 is also slotted longitudinally to receive a bar 28 adapted to engage the curved outer side of the bearing members 24 and slide thereon as these members rotate slightly with the eccentric 40 motion of the piston, and this bar or shoe 28 is forced toward and into firm contact with the surface of the bearing block members by means of coiled springs 29 so that a very tight joint of extended width and length is provided between 45 the bearing block members 24 and the concaved inner end surface of the wall or abutment 27. This abutment, because of its width and the close fit of its lateral shoulders against the curved surface of the cylinder wall, provides a very rigid 50 abutment and this abutment is further held against movement by one of the bolts 4 passing through the tongue or shank portion 27a of the abutment longitudinally thereof.

An inlet passage 30 is formed in the peripheral 55 ring member forming the outer wall or walls of the cylinder, this inlet passage opening into the cylinder adjacent one side of the abutment 27 and an outlet passage 31 is provided in the wall at the opposite side of the abutment, this outlet being 60 controlled by a poppet valve 32 so that back pressure will not enter the outlet side of the cylinder.

By locating the pivot pin 22 within the slot 21 of the two pistons to extend across both pistons within the cross sectional area of these pistons, a 65 very rigid pivot is provided upon which the pistons oscillate, and by providing half bearing blocks in the slot in each piston upon this pivot pin, these blocks completely fill the slot transversely and provide an extended area of contact between the 70 blocks and side walls of the slots and also between the blocks and pivot pin and between the blocks and the abutment wall 27 so that there is no possibility of leakage from the inlet to the outlet side

of the piston, and a tight joint is further insured by providing the shoe 28, which is spring pressed, against the curved outer surface of the bearing members. The wedge strip or shim 25 further insures against leakage past the bearing members and the arrangement provides a free oscillatory movement of each piston.

As shown, the tubular pivot pin 22 may be utilized as a conduit for lubricant, one end thereof being closed by a screw plug 32 and a pipe 33 inserted in its opposite end. Lubricant may thus be supplied to this pin and may escape laterally from its bore through holes bored radially and communicating with grooves formed in the side or contact surfaces of the bearing members 24 to provide oil conduits 34, lubricant also being supplied to the outer surface of the pivot member through these radial openings. This film of oil supplied to the contact surfaces of the bearing members 24 also assists in preventing leakage past these bearing members through the slot in which they are positioned.

Obviously changes may be made in the construction and arrangement of parts without departing from the spirit of the invention and I do not, therefore, wish to limit myself to the particular construction shown.

Having thus fully described my invention, what I claim is:—

1. A device of the character described comprising a cylinder having a peripheral wall and circular heads, a shaft mounted axially of said cylinder, an eccentric on said shaft, a circular piston in said cylinder upon said eccentric, said piston having a slot opening through the ends and periphery thereof, a pivot pin extending through said slot in said piston longitudinally of said slot and secured in the said cylinder heads, half bearing members in said slot upon said pin for rotation thereon with the oscillatory movement of said piston, the outer end of said pair of bearing members being curved concentric with the axis of said pin and said pair being of a length equal to the length of the piston in which it is mounted, and an abutment wall projecting into said cylinder from the peripheral wall thereof, said abutment wall being of a thickness substantially equal to the width of said slot in said piston and extending inward to adjacent the open outer side of said slot with its inner end surface curved to conform to the curvature of the outer surface of said pair of half bearing members, and means for yieldingly pressing one of said half bearings into close contact with one side of said pivot pin and through the rotative adjustment of said piston caused thereby, to press the other half bearing into contact with said pin and with the opposite side wall of said slot, said cylinder being formed with an inlet passage at one side of said abutment wall and an outlet passage at the opposite side.

2. A device of the character described and as characterized in claim 1, and wherein one side wall of said slot in said piston is formed by a shim member of plate form, and yieldable means is interposed between said shim and one side wall of said slot to force the said shim into firm contact with the adjacent surface of one half bearing and through the rotative adjustment of said piston caused by force applied to said shim, to force the opposite side wall of said slot into firm contact with the surface of said other half bearing.

JOHN O. HEINZE.
